[57] CLAIM

The ornamental design for football target, as shown and described.

DESCRIPTION

FIG. 1 is a perspective view of a football target showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

FIGS. (2-7 inclusive) are shown as fragmentary views and in an enlarged scale for ease of illustration.

FIG. 1

FIG. 4

FIG. 5

FIG. 6

FIG. 7
